COMBINED DOLL'S HEAD AND BASE

Joseph Paganello, Fairlawn, N.J.
(152-156 Wooster St., New York, N.Y. 10012)

Filed Mar. 4, 1969, Ser. No. 16,022

Term of patent 14 years

Int. Cl. D21—02

U.S. Cl. D34—4

FIG. 1 is a perspective view of a combined doll's head and base showing my new design,

FIG. 2 is a side elevation of a combined doll's head and base, and

FIG. 3 is a rear elevation of a combined doll's head and base therefor.

I claim:

The ornamental design for a combined doll's head and base, as shown.
